DESIGN FOR AN ILLUMINATED SIGN FRAME

Justin J. Rosenthal, Baltimore, Md.

Application February 25, 1937, Serial No. 67,860

Term of patent 3½ years

To all whom it may concern:

Be it known that I, Justin J. Rosenthal, a citizen of the United States, residing in the city of Baltimore, in the State of Maryland, have invented a new, original, and ornamental Design for an Illuminated Sign Frame of which the following is a specification, reference being had to the accompanying drawing, which forms a part thereof.

Fig. 1 is a front view of an illuminated sign frame, showing my new design.

Fig. 2 is a left-side elevation.

Fig. 3 is a sectional view across one of the horizontal intermediate frame-strips.

Fig. 4 is a sectional view across one of the vertical intermediate frame-strips.

The article consists of a multiplex frame 5 hinged to an easel-frame 6 including a reflecting pan 7 having electric bulbs 8 therein to illuminate translucent signs to be placed in the small frames constituting the multiplex frame 5.

I claim:

The ornamental design for an illuminated sign frame, as shown.

JUSTIN J. ROSENTHAL.
